UNITED STATES PATENT OFFICE.

MAURITZ ISIDOR HÖRLIN, OF STOCKHOLM, SWEDEN.

METHOD OF MANUFACTURING WAINGSCOTS.

Application filed December 10, 1921. Serial No. 521,484.

To all whom it may concern:

Be it known that I, MAURITZ ISIDOR HÖRLIN, citizen of Sweden, residing at Stockholm, Sweden, have invented certain new and useful Improvements in Methods of Manufacturing Wainscots, of which the following is a specification.

This invention relates to methods of making paneled surfaces such as walls, wainscots, ceilings, and the like.

This invention relates more particularly to the making of such paneled surfaces in situ employing panels attached to the surface by means of nails, screws and the like, and strips around said panels which assist in holding the latter to the surface and in some cases also conceal the heads of the nails or other fastenings.

The object of the invention is to provide an improved method of making such paneled surfaces in situ which shall be more expeditious and less expensive than existing methods.

Another object of the invention is to provide such a method which will allow for expansional movements of the panels.

Another object of the invention is to provide such a method in which all the nails or other fastenings will be concealed.

The method according to the present invention consists in securing panels with suitable spacing to the surface to be covered by means of fastenings applied near the edges of the panels, securing to said surface in the spaces between the panels, filling strips channeled at their front surface and having flanges overlapping the edges of the panels said filling strips being adapted to permit expansion of the panels, and inserting smaller strips in the channels of the filling strips.

In order that the invention may be fully understood, there will now be described by way of example and with reference to the accompanying drawings, a paneled wainscot in accordance with the invention.

In these drawings—

Fig. 1 illustrates the front view of the wainscot during different stages of manufacture; and

Fig. 2 is a section along the line A—B in Fig. 1.

In the drawings 1 denotes support-boards which are nailed to the wall.

On these support-boards the panels 2 are fixed by means of nails 3 or other fastenings, leaving spaces 4 between the panels, as shown in Figs. 1 and 2. The spaces 4 are adapted to receive filling strips 5, the base portions whereof lie in the spaces but are narrower than the distance between adjacent panels. These strips 5 are provided with flanges 14, extending over the edges of the panels so as to conceal the nails 3. To facilitate the insertion of the strips 5 in proper position guiding wires 8 of suitable form may be used, as shown in Fig. 2. The filling strips 5 are fixed to the support-boards 1 by means of screws 9. To conceal these latter, which are arranged in a central channel 10 in the filling strips 5, smaller strips 11 are fixed to the strips 5 for instance by gluing. If these smaller strips rise above the surface of the filling strips 5, they may be mitred in the points 12.

The form and profile of the strips and panels are of no importance in the present relation.

Thus for instance the small strips 11 do not need to extend over the surface of the filling strips 5 but may be wholly contained in the channels 10. In such a case the strips 11 of course are not mitred.

To facilitate the removing of the small strips 11 they are glued only at a few points or they may be merely pressed into the channels 10.

I claim:

The method of paneling walls, ceilings and like surfaces which consists in securing panels with suitable spacing to the surface by means of fastenings applied near the edges of the panels, securing to said surface in the spaces between the panels filling strips channeled at their front surface and having flanges overlapping the edges of the panels and said fastenings, said filling strips being adapted to permit expansion of the panels, and inserting smaller strips in the channels of the filling strips.

In testimony whereof I affix my signature in presence of two witnesses.

MAURITZ ISIDOR HÖRLIN.
